LUGGAGE HANDLE

Erwin Kalla, West Pittsburgh, Pa., assignor to Reliable Luggage, Inc., West Pittsburgh, Pa., a corporation of Pennsylvania

Application November 3, 1959, Serial No. 58,198

Term of patent 14 years

(Cl. D87—2)

Fig. 1 is a top plan view of a luggage handle, showing my new design;

Fig. 2 is a front elevation thereof;

Fig. 3 is an end view thereof;

Fig. 4 is a horizontal sectional view along line 4—4 of Fig. 2;

Fig. 5 is a vertical sectional view along line 5—5 of Fig. 2; and

Fig. 6 is a fragmentary enlarged front elevational view of the central portion of the handle shown in Fig. 2.

I claim:

The ornamental design for a luggage handle, as shown.
